D12-203. OR D 13,639 EX

DESIGN FOR A STEP-PAD.

Design No. 13,639, dated February 20, 1883.

UNITED STATES PATENT OFFICE.

JOHN L. POPE, OF CLEVELAND, OHIO.

DESIGN FOR A STEP-PAD.

SPECIFICATION forming part of Design No. 13,639, dated February 20, 1883.

Application filed November 28, 1882. Term of patent 14 years.

To all whom it may concern:

Be it known that I, JOHN L. POPE, of Cleveland, in the county of Cuyahoga and State of Ohio, have invented and produced a new and original Design for Step-Pads, of which the following is a specification, reference being had to the accompanying photograph, making a part hereof.

My invention relates to a novel design for 10 step-pads for use in connection with carriages and other vehicles; and it consists in certain features of ornamentation, which will be hereinafter fully described and claimed.

In the accompanying photograph will be 15 seen in top plan view a metallic step-pad made according to my new design. The general shape or outline of the article is rectangular, and its outer edges are rounded or curved, and all around its sides runs a border of rib-work, (designated by the letter *a*.) The upper surface of this plate or pad is further ornamented by a series of X-shaped figures, disposed diagonally of the plate. These figures will be found marked with the letter *b*, 20 and whether viewed from either the sides or ends of the plate have the appearance of the letter X, made of raised or bar work; but when viewed from either corner of the step they then look to be like crosses. As will be seen, the

ends of these figures are beveled or slanting, 30 which tends to improve considerably the beauty of design of the plate. Connecting the border *a*, all around the step, are a lot of V-shaped figures made of short ribs. These figures are in reality halves of X-shaped figures, 35 and if they were continued out a like distance past the border they would have shapes just like those marked *b* in the photograph.

What I claim as new, and desire to secure by Design Letters Patent, is—

1. A step-pad of the design shown and described.
2. A step-pad the upper surface of which is ornamented by figures like those marked *b*, disposed as shown and described.
3. A step-pad the upper surface of which is ornamented with figures *b*, disposed as shown, and with a raised border substantially like that marked *a*.

4. A step-pad ornamented with X-shaped 50 figures—such as *b*—the ends or extremities of which are beveled, as shown and described.

In witness whereof I have hereunto set my hand this 16th day of November, 1882.

JOHN L. POPE.

In presence of—

WALTER A. BIDDLE,
H. CLARK FORD.
